GUY WIRE GUARD

Burton M. Smalley, Chicago, Ill., assignor to
Joslyn Manufacturing & Supply Co., Chicago,
Ill., a corporation of Illinois

Application August 13, 1931. Serial No. 556,724

8 Claims. (Cl. 189—31.5)

This invention relates to guards for guy wires and the like.

It is old in the art to provide guards for guy wires such as are used to support the poles of an overhead electrical distribution system, which guards render the guy wires more conspicuous and thereby prevent pedestrians from accidentally running into the wire and injuring themselves. Among these prior art devices of which 10 I am aware are all metallic guards which are attached to the guy wire and guy rods, and serve to protect the guy as well as to render it more conspicuous. Other prior art devices consist of a wooden member grooved to receive the guy wire 15 to which it is attached.

My present invention provides a new and improved guard of this type, consisting preferably of a grooved non-metallic member for the upper part of the guard and a metallic member rigidly 20 secured to the non-metallic portion of the guard and adapted to fit over the guy rod and clamp by which the guy wire is attached to it. My improved guard is very economical to manufacture and install, is light in weight, and is fool- 25 proof for the reason that it is impossible for a lineman to install it in any manner except that in which it is intended that it should be installed. The grooved non-metallic upper portion of the guard automatically spaces it with respect to the wire so that the installation, when 30 completed is of pleasing appearance, and therefore does not detract from the appearance of the pole line. The guard may be conveniently painted with a conspicuously colored paint, such as for example a metallic paint, and when installed can be seen for a considerable distance.

My invention will be best understood by reference to the accompanying drawing in which a preferred embodiment of it is shown by way of 40 example and in which:

Figure 1 is an elevational view partly in section of the guard attached to a guy wire and rod;

Figure 2 is a cross section of the guard taken along the line 2—2 of Figure 1 looking in the 45 direction of the arrows;

Figure 3 is a cross sectional view of the guard taken substantially along the line 3—3 of Figure 1 looking in the direction of the arrows;

Figure 4 is a similar cross sectional view taken 50 along the line 4—4 of Figure 1 looking in the direction of the arrows; and

Figure 5 is a cross sectional view taken along the line 5—5 of Figure 1 looking in the direction of the arrows.

55 Referring now to the drawing in more detail,

the guy that is to be guarded comprises a guy wire 1 which is usually a stranded cable, a guy rod 2 which is usually a solid metallic rod which terminates in a closed eyelet 3 through which the wire 1 is projected and clamped by means of suitable clamping devices 4.

My improved guard preferably consists of a wooden member 10 of generally rectangular cross section and contains a groove 11 running longitudinally through it. The groove 11 is of sufficient width to readily receive the guy wire 1, and is of a depth greater than its width, so that when the guy wire is disposed in the groove it is embedded in the guard member. While the member 10 is preferably composed of wood, or similar fibrous material, other suitable non-metallic substances may be substituted if desired. Wood is advantageous for the reason that it is economical, and has great strength per unit cost, that is, a given amount of money will buy more strength in wood than in most other materials. Wood is also light in weight, and the total weight of the guard is therefore low and its application to the guy wire does not unduly burden that wire with weight.

The bottom portion 12 of the groove 11 is spaced away from and located parallel to the uppermost portion 13 of the guard member 10, so that when the wire 1 is disposed in the bottom of the groove the guard is spaced automatically along the wire in a slightly manner.

The lower portion of my improved guard preferably comprises a sheet metal member 20 which is lapped over and attached to the lower end of the wooden member 10 as indicated at 21. This attachment may be made in any preferred manner such as by wood screws 22 which may conveniently be brass or iron screws. The end portion of the metallic guard 20 which engages the wooden member 10 is of course shaped to conform to the shape of the wooden member. The remaining portion of the metallic member is preferably substantially semi-circular in shape as shown at 23. The radius of this portion of the guard is made sufficiently large so that the clamp 4 by which the strand 1 is attached to the guy rod 2 will loosely fit within it, and the member 20 is sufficiently long so that when the clamps are disposed within it the guy wires of the guard extend well down over the clamps 4 to conceal them and to prevent a pedestrian from tearing his clothing by coming into contact with them.

Located within the metallic member 20 and adjacent its lower end is a metallic spacing block 24 which is perforated with a pair of parallel

holes through which the legs 25 of a U bolt 26 are projected. The closed end of the U bolt 26 encircles the guy rod 22 and draws it into an arcuate groove 27 in the spacing block 24. A 5 suitable tandem washer 28 is placed over the projecting ends of the legs 25 of the U bolt and positioned against the upper face of the guard 20. Nuts 29 threaded onto the bolts draw the washer 28 tightly down on the guard 20 and 10 cause the U bolts 26 to tightly clamp the guy rod 2 in place in the slot 27. This securely binds the lower end of the guard to the guy rod, and since this guy rod is composed of solid metal and is firmly embedded in the ground, the guard 15 is very securely held. The guy rod 2 does not tend to twist and turn, and therefore the guard will not tend to twist or turn.

The lowermost edge of the guard may be cut away at an angle as shown at 30 in Figure 1; 20 however, if desired, any other particular shape may be used within the teachings of my invention.

The uppermost end of the guard member 10 contains a U bolt 32 whose parallel legs 33 are projected through suitable openings in the member 10. The closed end of the bolt 32 is disposed transversely of the longitudinal slot 11 through the member, and adapted to encircle the guy wire 1, and to draw it in place in the bottom of 25 the slot. Washers 34 are threaded over the projecting upper ends of the U bolt 32, and nuts 35 are threaded thereon to draw the bolt tightly in place to thereby bind the guy wire 1 tightly against the bottom of the groove 11. This 30 securely binds the guard to the guy wire, and since the bottom of the slot 11 is aligned parallel with the upper face of the member 10, the member 10 is automatically aligned with respect to the guy wire and its application presents a 35 slightly appearance.

The metallic member 20 can conveniently be made of sheet iron of suitable thickness to give it the requisite strength, and I have found that 40 fourteen gauge sheet steel is adaptable for this purpose. The steel is coated with a protective coating, preferably applied by the hot galvanizing process, to prevent it from rusting. The wooden member 10 may be painted with suitable paint to render it more conspicuous. I have 45 found that a paint composed of metallic aluminum is very satisfactory for this purpose and that when the guard is so painted the appearance of it is made sufficiently conspicuous to permit a pedestrian to readily see it. The bolts 50 and nuts employed to bind the guard upon the guy wire and rod may also be composed of iron coated with a rust-proofing compound such as for example, zinc applied by a hot galvanizing process.

60 While I have chosen to show my invention by illustrating a preferred embodiment of it I have done so by way of example only as there are many modifications and adaptations which can be made by one skilled in the art within the 65 teachings of the invention.

Having thus complied with the statutes and shown and described a preferred embodiment of my invention what I consider new and desire to have protected by Letters Patent is pointed 70 out in the appended claims.

What is claimed is:

1. A guard for covering a guy wire, the guy rod to which it is attached and the clamping means by which it is attached thereto, comprising 75 a grooved wooden member fitted over the

guy wire, an arcuate metallic member secured to the wooden member and fitted over the clamping means and guy rod, a U bolt projected through the wooden member and encircling the wire to attach the guard to it, and a U bolt projected through the metallic member and encircling the guy rod to attach the guard to it. 80

2. A guard for covering a guy wire, the guy rod to which it is attached and the clamping means by which it is attached thereto, comprising 85 a grooved wooden member fitted over the guy wire, an arcuate metallic member secured to the wooden member and fitted over the clamping means and guy rod, and means for securely attaching said members to the guy wire and guy rod respectively. 90

3. A guard for guy wires comprising an elongated grooved wooden member for receiving a guy wire, a U clamp in said member for engaging the wire to attach the guard thereto, a metallic extension attached to one end of said member and projecting therefrom, a spacing block attached to said metallic extension near its free end, and a clamping member extended through said metallic extension and around said 100 block for engaging the guy rod to which said wire is attached to attach the guard to it. 95

4. A guard for guy wires comprising an elongated grooved member composed of fibrous material for receiving a guy wire, means in said 105 member for encircling the wire to attach the guard thereto, a substantially semi-circular extension on said member for receiving the guy rod and clamp by which the wire is attached to it, and means in said extension for engaging 110 the guy rod to attach the guard thereto.

5. A guard for guy wires comprising an elongated wooden member of generally rectangular cross section and containing a groove extending longitudinally of it, a metallic member attached to the wooden member and projecting from it, said projection being arcuate in section, a clamping means attached to the wooden member, and spacing and clamping means attached 115 to said metallic member, said means engaging 120 the guy wire and guy rod respectively to attach the guard to the guy.

6. A guard for guy wires comprising an elongated wooden member of generally rectangular cross section and containing a groove extending 125 longitudinally of it, a metallic member attached to the wooden member and projecting from it, said projection being arcuate in section, a U shaped clamping means projected through said wooden member and disposed with its closed end 130 extending transversely through said groove, and spacing and clamping means attached to said metallic member, said means engaging the guy wire and guy rod respectively to attach the guard to the guy. 135

7. A guard for guy wires comprising an elongated wooden member of generally rectangular cross section and containing a groove extending longitudinally of it, a metallic member attached to the wooden member and projecting from it, 140 said projection being arcuate in section, a U shaped clamping means projected through said wooden member and disposed with its closed end extending transversely through said groove, a grooved spacing block attached to said metallic 145 member adjacent its free end, a U shaped clamping means projected through said block and metallic member and disposed with its closed end extending transversely across the groove in said block, said first means engaging the guy wire 150

to clamp the guard to it and said latter means engaging the guy rod to clamp the guard to it.

8. A guard for guy wires and the like comprising, a non-metallic member having a longitudinal groove at its bottom for receiving a guy, a metallic member projecting from one end of

the non-metallic member and spaced from the guy by the non-metallic member, and means extending through the non-metallic member for securing the guard to the guy.
